DOOR CONTROLLING DEVICE

Wallace F. Moore, New Britain, Conn., assignor
to The American Hardware Corporation, New
Britain, Conn., a corporation of Connecticut

Application March 14, 1932, Serial No. 598,635
Renewed July 23, 1934

8 Claims. (Cl. 189—49)

My invention relates to door checks and closers, and has special reference to such devices that are particularly adapted for use in electrically controlled systems and apparatus for controlling doors.

One of the objects of my invention is to provide a novel and improved device of this character.

Another of the objects of my invention is to provide a device of this character that is capable of being controlled either by means of a fuse when the temperature of the room reaches a predetermined degree, or by electrically operated means.

15 The several features of the invention, whereby the above-mentioned and other objects may be attained, will be readily understood from the following description and accompanying drawing, in which:

20 Figure 1 is a side view, partly in section, of a door check embodying the features of my invention in their preferred form shown applied to a door and door case, the door being open;

Fig. 2 is a plan view of the same; and

25 Fig. 3 is a sectional elevation, on an enlarged scale, taken on the line 3—3 of Fig. 2.

30 My improved door check, as illustrated in the drawing, is particularly adapted for use in the systems and apparatus described and claimed in my pending applications Ser. No. 459,677, filed

June 7, 1930 and Ser. No. 543,400 filed June 10, 1931. The door check is shown applied to a door frame or case 2 and a door 4, the door being shown open. The check comprises the usual casing 6, the casing enclosing the usual fluid operable piston and door closing spring (not shown). A spring actuated door-closing arm 8 is connected by a loop 10, connecting-rod 12, and a bracket 14 to the door frame. The spring actuated arm 8 carries a double detent or pawl 16 for engagement with the teeth of a ratchet wheel 18 connected with the door closing spring in the usual manner.

45 A ring 20 is adjustably secured to the upper end of the case 6 and carries a plate 22 having a pocket 24. This pocket 24 is adapted to receive a downwardly spring pressed detent 26 carried by a spring actuated arm 8. When the detent is received in its said pocket and its spring is under tension, it is adapted to hold the door open. This detent comprises a steel ball which is received in the lower end of a vertical aperture 28 in the spring actuated arm 8. The detent ball is pressed downwardly when in said pocket by means of a

plunger 30 mounted in said aperture which in turn is acted upon by a coiled spring 32 interposed between the upper end of the plunger and a screw plug 34. The downwardly spring pressed plunger 30 is provided with a flange that engages a shoulder in the aperture 28 to limit the downward movement of the plunger so that when the ball 26 rides out of its pocket and as it reaches the end of the plate 22, it drops out of engagement with the lower end of the plunger and thus rotates freely during the completion of the closing of the door.

5 The door check is further provided with means for releasing the tension of the detent spring 32 so as to render said spring and its associated detent plunger 30 inoperative to hold the detent ball 26 in its pocket, and thus permit the spring actuated arm 8 to close the door. This means comprises a lever 36 mounted on the top side of the spring actuated arm 8. One end of this lever 20 is provided with a recess 38 which loosely receives the upper end of a boss 40 on the arm 8, the aperture 28 extending through this boss. This recess 38 is provided with an aperture through which is screw-threaded the abutment plug 34 for the detent spring 32. The lever 36 is detachably fulcrumed on the arm 8 by means of an inwardly directed tongue or lug 42 which is received in a slot in the side of the boss 40. The outer end of the lever 36 is held down by means hereinafter 25 described.

30 The top side of the door closing arm is provided with a member 44 which has a recess 46 for receiving the outer portion of the lever 36 when the device is in normal position. The under side of the lever 36 is provided with a shoulder 48 which is arranged adjacent the outer face of the member 44.

35 A post 50 is pivoted at its upper end in a recess in the under side of the lever 36. This post extends downwardly through an elongated aperture in the arm 8 and its lower end is provided with laterally projecting shoulders, one of which is shown at 52. The sides of the post 50 are flattened and arranged closely adjacent the side walls 40 of the aperture through which it extends.

45 Upon releasing the outer end of the lever 36 the detent spring 32 acts immediately to throw said lever upwardly about the axis of the fulcrum formed by the lug 42. Also, as the lateral shoulder 52 on the post 50 strikes the under side of the arm 8 the lever is forced forwardly a sufficient distance to disengage the fulcrum lug 42 from the upper wall of the slot in which it is received. Thus upon the outer end of the lever 36 being re- 50 55

leased, the spring actuated arm 16 is permitted immediately to close the door.

The door closing arm is provided with an opening 54 formed by means of an enlarged collar 5 portion 55 on the arm beneath the forward end portion of the lever 36. The lever 36 is held down by means of a trigger or trip 56 that is connected with the lever by means hereinafter described. The trip 56 is pivoted on pins 58 with- 10 in a casing 60 secured to the under side of a plate 61 secured across the collar portion 55. The trip 56 is normally held in horizontal position by means comprising an armature 70 which when drawn back from the position shown in 15 Fig. 1 releases the trip. The armature is adapted to be thus drawn back by means of electromagnets 72 when the latter are energized.

When the lever 36 is released, circuit connection with the electro-magnets 72 is broken 20 and cannot be accidentally re-established. To accomplish this, the lead wire from one of the electro-magnets is grounded on the spring actuated arm 36. The other lead wire from the magnet is attached to the binding post 74 which in 25 turn is connected to one side of a power supply (not shown). The other binding post 76 is connected to a spring 78 which is secured to a block of insulating material 80 so as to be insulated from the spring actuated arm. This contact 30 spring 78 has a tongue extended between up-standing lugs formed on the block 80. These lugs receive between them the forward portion of the lever 36, so that when the lever is held down, the under side of the arm is held in electrical 35 contact with the contact spring 78. When, however, the lever is released it is immediately disengaged from the contact spring so as to open the circuit.

In order to insure against the circuit being 40 accidentally closed by the lever 36 dropping, a flat spring 82 is secured to a side of the lever 36 which by engaging the end of one of the lugs on the block 80 prevents the lever 36 from falling back into contact with the contact spring 78.

45 Except as hereinafter described, the parts above referred to may be and preferably are the same as the corresponding parts of the door check described and claimed in my said pending application Ser. No. 543,400.

50 In accordance with the present invention the connection between the end of the lever 36 and the trip 56 comprises a two-part fuse 84 having apertures in its ends that are hooked over the ends of said lever and trip, the said ends of these 55 parts being provided with recesses in which the ends of the fuse are received. The fuse 84 extends through the clearance opening 54 in the spring actuated arm.

60 Normally during opening and closing the door, the door-check operates in the usual manner. When the circuit connection with the electro-magnets is closed, the trip 56 is released allowing the arm 36 to be thrown upwardly to release the detent 26 from the holding pocket in the 65 stop plate 22. As the arm springs upwardly, the fuse 84 is pulled off of the end of the trip 56 and by the force of the upward movement of the lever 36, is thrown outwardly and away from the end of said lever so that there is no danger of these 70 parts being accidentally re-connected.

75 Also, when the temperature in the room reaches a predetermined degree, the fuse 84 is broken, thus, also allowing the lever 36 to be thrown upwardly to release the detent 26 to permit the spring actuated arm to close the door. As the

5 fuse is broken, the part thereof on the end of the arm 36 is thrown upwardly and off the arm so that there is no danger of the two parts becoming accidentally connected together again.

From the foregoing it will be apparent that my improved device may operate to close the door either upon energizing the electro-magnet or upon the breaking of the fuse 84. The device is particularly adapted for use where the circuit connection with the electro-magnet is controlled 10 by a thermostat, either located in the same room with the device or in another part of the building. In such case in the event of the failure of the power supply to the device, the fusible link would 15 fuse and thus cause the device to operate to close the door. The device may also be used where the circuit connection with the electro-magnet is controlled by any other form of switch whether hand or otherwise operated. Also, it will be apparent that any number of my improved door 20 checks can be used and controlled by any number of thermostats or other switching devices.

As will be evident to those skilled in the art, my invention permits various modifications without departing from the spirit thereof or the scope 25 of the appended claims.

What I claim is:

1. The combination of a door, a door-closer comprising a spring tending to close the door, means comprising a device serving when held in 30 one position to hold the door open against the tension of said spring and adapted to be released to permit the spring to close the door, and means for maintaining said device in door-holding position comprising a fuse serving when broken to 35 release, said device and electrically controllable means adapted to be operated to release said device.

2. The combination of a door, a door-closer comprising a spring tending to close the door, 40 means comprising a device serving when held in one position to hold the door open against the tension of said spring and adapted to be released to permit said spring to close the door, and means for maintaining said device in door-holding position comprising electrically controllable means and connection between the latter and said holding device comprising a fuse whereby said holding device may be released either by operation of 45 said electrically controllable means or breaking of said fuse.

3. The combination of a door, a door-closer comprising a spring tending to close the door, means comprising a device serving when held in 55 one position to hold the door open against the tension of said spring and adapted to be released to permit said spring to close the door, and means for maintaining said device in door-holding position comprising a retaining member, means for holding said member in fixed position, electrically controllable means for releasing said member, and means comprising a fuse connecting said member with said holding device whereby either upon breaking of the fuse or 60 release of said member said holding device is released.

4. The combination of a door, a door-closer comprising a spring tending to close the door, means comprising a device serving when held 70 in one position to hold the door open against the tension of said spring and adapted to be released to permit the spring to close the door, and means for maintaining said device in door-holding position comprising a fuse serving when 75

broken to release said device and electrically controllable means adapted to be operated to release said device, and means acting automatically upon breaking of the fuse to break the circuit connection with said electrically controllable means.

5. The combination of a door, a door-closer comprising a spring tending to close the door, means comprising a device serving when held in one position to hold the door open against the tension of said spring and adapted to be released to permit the spring to close the door, and means for maintaining said device in door-holding position comprising a fuse serving when broken to release said device, and electrically controllable means adapted to be operated to release said device, and means acting automatically upon releasing said device either upon breaking of the fuse or on operation of said electrically controllable means to break the circuit connection with said electrically controllable means.

10. In a door closer, the combination of means comprising a spring tending to close the door, a holding device for holding the door open against the tension of the spring, means comprising a fuse for releasing the holding device upon breakage of the fuse, a latching device, said fuse being connected with said holding device and latching device, and electrically con-

trolled means for operating said latching device to release the holding device prior to the breaking of the fuse.

15. In a door closer, the combination of a spring actuated door closing arm, a stop member, a holding device associated with the arm and adapted when in one position to engage the stop member when the door is open, latching means carried by said arm, means connecting said holding device and latching means comprising a fuse and electrically controlled means for operating said latching means to release the holding device.

20. In a door closer, the combination of a spring actuated door closing arm, a stop member, a detent carried by said arm and adapted to engage said stop member when the door is open, a spring for maintaining said detent in holding engagement with said stop member to hold the door open when the spring is under tension, a holding device when in one position adapted to hold the spring under tension, means for maintaining said holding device in position comprising a latching device, a fusible link connecting said holding device and latching device, and electrically controlled means for operating said latching device to release the holding device.

25. WALLACE F. MOORE.
